Atty's

UNITED STATES PATENT OFFICE.

WILLIAM L. WALKER, OF NEW YORK, N. Y.

VAULT LIGHT.

Application filed May 3, 1919. Serial No. 294,380.

To all whom it may concern:

Be it known that I, WILLIAM L. WALKER, a citizen of the United States, and resident of New York city, in the county of New York and State of New York, have invented new and useful Improvements in Vault Lights, of which the following is a specification.

This invention relates to lights of the general type comprising essentially a plurality of lenses suitably secured within a frame, such as are commonly used for lighting vaults, basements, cellars and the like. Its principal object is to provide a lens which can be readily and securely installed with an air tight and water tight joint between it and the frame and which at the same time is readily removable as the lens becomes chipped or broken in service.

Referring to the drawings which illustrate certain embodiments of my invention,—

Figure 1 is a vertical central section of my improved lens and frame;

Figure 2 is a similar view of a modified form;

Figure 3 is a similar view, the lens being shown in elevation and having a modified form of packing ring.

Figure 4 is an elevational view of a further modified form of lens; and

Figure 5 is a top view of a section of a vault light showing a lens mounted in its support.

Referring to Fig. 1, A is an annular supporting member cast integrally with the usual vault light frame or such as disclosed in my co-pending application Serial No. 294,381, filed May 3, 1919, and tapered downwardly so as to form a support for the lens glass B adapted to be placed therein. B is the lens glass having a taper corresponding to the taper of the member A. The lens B is provided with a rectangular circumferential groove B¹ in which is placed a gasket G of rubber or other compressible deformable material of rectangular cross section. To secure the lens B in the member A the lens B is provided with T-shaped grooves B² on opposite sides of the lens B adapted to receive bolts C, and the member A is provided with inturned lugs A² through which the bolts pass. The bolts are threaded on their lower ends to receive clamping nuts N. Surrounding the bolts between the lens B and the lugs A² are lead washers W to serve as bearings for the lens and to prevent the

lens from sinking too deeply into the annular member. The space above the gasket G and between the lens B and the member A is filled with a mixture of sulphur and tar T for the purpose of keeping water and oil away from the gasket G.

After the vault light frame has been filled with cement or like material, the rubber gasket G is snapped into the groove B¹, the bolts C are inserted in the grooves B², and the lens is then inserted in the member A with the threaded ends of the bolts projecting through the lugs A². The nuts N are then placed on the bolts and turned up until a bearing is obtained between the lens, lead washers W, and lugs A². As the lens is drawn into the member A, the gasket G becomes compressed and assumes the form shown in Fig. 1. After the lens has been securely fastened, sulphur-tar composition T is poured into the space between the lens B and member A, and allowed to cool. The lens is thus securely held in the member A, making a water-tight connection therewith.

Instead of a rubber gasket I may use a lead gasket in the form of a lead ring G¹, square in cross section and cast in the groove B¹ of the lens B. This embodiment is illustrated in Fig. 2. When the lens B is drawn into the member A, the lead gasket G¹ becomes compressed and flows to form a tight joint between the lens and the supporting member A. The lead gasket could also be formed from a strip of lead and the ends burned together after placing it in the groove of the lens. While I have shown the lens B in Fig. 2 as having perpendicular sides it is evident that it could be formed as well with sloping sides similar to the embodiment shown in Fig. 1.

I may also employ a gasket of metal such as copper, brass or other reasonably soft metal. As such metals have a high melting point they cannot therefore be cast in the groove in the lens, and must therefore be formed into the proper shape and with a proper diameter to fit the groove in the lens and inserted into the groove. To provide for this I form the ring split or with a diagonal cleft in order that the ring may be sprung open and slipped over the lens into the groove. Fig. 3 illustrates such a gasket G² provided with a cleft D. This construction is similar to that of a piston ring.

Fig. 4 shows an embodiment of the lens B, similar to Fig. 1 except that the circumfer-

ential groove is semicircular instead of rectangular and that a gasket G^3 of circular cross-section is employed therewith.

The lens B could be held into the member 5 A by means of cotter pins or bent wire as shown at P in Figs. 3 and 4, in place of the bolts C shown in Figs. 1 and 2. When so employed the split end of pin P would pass through the lug A^2 and be spread open as is 10 the usual practice with cotter pins.

The construction above described is simple and provides efficient means for securing the lens and for its removal in case of breakage. The narrow rubber gasket is easily 15 made and inserted in the groove of the lens and insures a tight joint between the lens and its support, and is efficiently protected from water and oil by the sulphur-tar composition which is inserted above the gasket. 20 If desirable the lens could be made square or oblong and a rubber gasket of the same form used therewith. A further essential feature of the invention resides in the use of deformable metal gaskets which would be 25 far more durable than rubber and yet provide a water-tight joint between the lens and its support.

While in some of the figures I have shown lenses with circumferential grooves of rectangular cross section and in other figures lenses with grooves of semi-circular cross-section, it is obvious that lenses could be employed having grooves of other cross-section the lenses being supplied with gaskets having a cross-section similar to the cross-section of the groove. It is further obvious that the nature of the material used to form the gasket is independent of the shape of the groove in which the gasket is to be employed. 30

40 I claim:

1. A vault light, comprising a supporting member, a lens in said member having a circumferential groove, a gasket in said groove for the purpose of providing a water-tight joint between said member and said lens, and sealing material above said gasket and between said lens and said member. 45

2. A vault light, comprising a supporting member, a lens in said member having a circumferential groove, axial grooves on opposite sides of said lens, lugs on said member, means engaging said axial grooves and passing through said lugs for the purpose of securing said lens in said member and a soft 55 metal washer between said lens and said lugs and surrounding said means and upon which said lens is brought to bear.

3. A vault light, comprising a supporting member, a lens in said member having a circumferential groove, axial grooves on opposite sides of said lens, lugs on said member, means engaging in said axial grooves and passing through said lugs for the purpose of securing said lens in said member and a lead 60 washer between said lens and said lugs and

surrounding said means and upon which said lens is brought to bear.

4. A vault light comprising a supporting member, a lens in said member having a circumferential groove, axial grooves on opposite sides of said lens, lugs on said member, cotter pins engaging in said axial grooves and passing through said lugs for the purpose of securing said lens in said member and a soft metal washer between said lens and said lugs and surrounding said cotter pins and upon which said lens is brought to bear. 75

5. A vault light, comprising a supporting member, a lens in said member having a circumferential groove and a split metal gasket in said groove for the purpose of providing a water-tight joint between said member and said lens. 80

6. A vault light, comprising a supporting member, a lens in said member having a circumferential groove a deformable metal gasket in said groove for the purpose of providing a water-tight joint between said member and said lens and sealing material above 90 said gasket.

7. A vault light comprising a supporting member having an opening thereto, a lens member fitted in the opening of said supporting member, a deformable gasket between the surfaces of contact of the members, and a sealing material of plastic condition when applied, completely filling any interstices between the surfaces of contact of the members above said gasket. 95

8. A vault light comprising a supporting member having a socket therein, a lens substantially fitting said socket, a soft metal gasket between said lens and said support and sealing material above said gasket. 105

9. A vault light comprising a supporting member, a transparent member in said first member, a groove in one of said members, a gasket in said groove for the purpose of providing a water tight joint between said members, and sealing material above said gasket and between said members. 110

10. A vault light comprising a supporting member, a transparent member in said first member, a groove in one of said members, a soft metal gasket in said groove for the purpose of providing a water tight joint between said members, and sealing material above said gasket and between said members. 115

11. A vault light comprising a supporting member, a transparent member in said first member, a groove in one of said members, a split metal gasket in said groove for the purpose of providing a water tight joint between said members, and sealing material above said gasket and between said members. 120

Signed by me at New York city this 25th day of April, 1919.

WILLIAM L. WALKER.
